UNITED STATES PATENT OFFICE

JOSEPH HARRINGTON, OF RIVERSIDE, ILLINOIS, ASSIGNOR TO JOSEPH HARRINGTON COMPANY, OF HARVEY, ILLINOIS, A CORPORATION OF ILLINOIS

METALLURGICAL FURNACE

Application filed March 2, 1928. Serial No. 258,473.

The invention relates generally to metallurgical furnaces and more particularly to those furnaces which heat annealing ovens and the like and are fed with fuel by mechanical stokers.

In furnaces of this character it is essential that a pressure which is greater than that of the surrounding air be built up within the furnace and oven to insure positively the exclusion of air when the oven doors are opened for the insertion and removal of the metallic slabs or sheets, for the reason that such air containing its usual percentage of oxygen instantly, upon entering the oven, becomes highly heated and when brought into contact with the slabs causes a scaling or oxidation of the metal which is extremely injurious to the product and results in great waste. It is now common practice to create

a definite pressure within the furnace and oven which exceeds that of atmosphere and is sufficient to cause an actual escape of the flames and gases when the charging doors are opened by utilizing a forced blast system

that includes a conduit for the air under pressure having an outlet positioned beneath the stoker. Since there is a restriction to the passage of the gases from the furnace to the oven or annealing chamber, it is necessary

with such an arrangement to develop an exceedingly high pressure within the furnace in order to have the gases in the oven under the desired and necessary pressure. This

comparatively high pressure in the furnace is efficient in that it insures the exclusion of the surrounding air and effectively prevents scaling of the metal slabs, is objectionable because it operates to force the hot and deleterious furnace gases through the inter-

stices of the brickwork and the openings around the stoker or grate firing doors. These gases not only result in injury to the stoker, parts being broken away for illustrative purposes;

but also poison the air in which the operatives work.

The primary object of the present invention is to prevent the unauthorized escape of gases from furnaces of the aforementioned type. In general, this object is attained by enclosing the front of the furnace together

with the exposed parts of the stoker mechanism in an air-tight chamber into which air is forced under a pressure in excess of that within the furnace. The pressure developed within the chamber or enclosing structure is applied to the external surface of the furnace and the exposed parts of the stoker and prevents the escape or infiltration of the noxious gases through the interstices of the brick-work and the usual furnace openings. Thus poisoning of the surrounding air and injury to the stoker mechanism and brickwork is effectively avoided.

Another object of the invention is to provide a structure for hermetically sealing the front of metallurgical furnaces, which structure is of an improved character and may be readily and quickly assembled at the place of installation.

A further object of the invention is to provide a furnace which, in its entirety, is of new and improved construction.

Other objects will be manifest as the description proceeds.

The invention consists in the several novel features hereinafter set forth and more particularly defined by the claims at the conclusion hereof.

In the drawings which accompany and form a part of this disclosure and in which like numerals and characters of reference denote like or corresponding parts throughout the several views:

Figure 1 is a vertical longitudinal section of an annealing furnace provided with an enclosing structure embodying the invention;

Figure 2 is a transverse section taken on the line 2-2 of Figure 1;

Figure 3 is a horizontal section taken on the line 3-3 of Figure 1;

Figure 4 is a perspective of the mechanical brickwork, tile and stoker operating mechanism, but also poison the air in which the operatives work.

Figure 5 is a detail view of the gearing for driving the various reciprocating elements of the stoker; and

Figure 6 is a detail view of the fan for putting the air in the enclosing structure under pressure.

The invention is exemplified in connection

with an apparatus for annealing metallic slabs or sheets d . This apparatus consists of a furnace A which heats an oven B containing the slabs. The furnace A is fed with fuel by a mechanical stoker C and comprises a back wall a , side walls a' and a^2 and a top wall a^3 . These walls are made of firebrick and together form a combustion chamber a^4 over the grate bars of the stoker. An ignition arch is formed at the front of the furnace by a longitudinal series of arcuate members a^5 which have their ends disposed and supported in pockets or sockets a^6 formed in the side walls. A vertical series of tiles a^7 forms a bridge wall or baffle device at the rear of the furnace. These tiles are staggered or offset with respect to each other and are supported by an I-beam a^8 which rests upon an integral part of the back wall a . The floor upon which the furnace is supported is recessed to form an ash pit a^9 . A passageway a^{10} is cut in the side wall a^2 adjacent the combustion chamber a^4 and conducts the products of combustion from the furnace to the annealing oven B. The latter is arranged at one side of the furnace and comprises a back wall b , a side wall b' , a top wall b^2 , and a front wall b^3 which are made of firebrick and together form a heating chamber b^4 . The front wall is provided with an opening b^5 through which the slabs or sheets d are inserted into the oven, and the back wall b has a discharge opening b^6 . These openings are normally closed by doors b^7 . Rails b^8 are secured to the floor b^9 of the oven and permit the slabs to be slid through the heating chamber by the use of a hydraulically operated mechanism, as well understood in the art. The side wall a^2 of the furnace forms the inner side of the oven. The top wall a^3 embodies an arcuate section a^{11} which extends over the rear end of the stoker C and is shaped to direct the products of combustion laterally and into the passageway a^{10} . The annealing oven extends rearwardly from said passageway and is provided with a valve controlled chimney or outlet duct (not shown).

The stoker C is in the form of a unit which fits into the front end of the furnace and comprises a pair of sides c , c' which are rigidly connected together and are held in spaced relation by cross bars c^2 . An inclined member c^3 extends between the front ends of the sides and forms a hopper. Beneath this member is a horizontally movable plate c^4 which feeds the fuel from the hopper to a stepped grate mechanism consisting of a pair of horizontal movable sections c^5 and c^7 and a pair of stationary sections c^6 and c^8 which alternate with the movable ones. The sections are each made up of a plurality of grate bars c^9 which are suitably spaced apart to form the necessary draft openings therebetween. The plate c^4 has its side margins bent downwardly to form supporting strips c^{10} which rest upon flanged rollers c^{11} . The latter are individually supported by tracks c^{12} which are connected to the sides of the stoker and have stop lugs c^{13} at the ends thereof. The rear end of the plate c^4 is connected to the contiguous end of the section c^5 so that the fuel will be fed directly and said section will be reciprocated by the mechanism that is employed in connection with the plate. The stationary section c^8 is supported at its front end by a block c^{14} which is formed of tile or firebrick and is suitably secured to the sides c and c' . The rear end of section c^8 rests upon a girder c^{15} which is in the form of a cylinder and is secured in place similarly to the block c^{14} . The rear end of the section c^7 rests and slides upon the front end of section c^8 while the front end is connected to a transversely extending bar c^{16} which is secured to the distal ends of a pair of operating links c^{17} . The latter are movably supported upon a pair of flanged rollers c^{18} which travel on tracks c^{19} . The fixed or stationary section c^6 is supported at its rear end upon the front end of section c^7 and at its front end by a bracket c^{20} which extends between and is secured to the sides of the stoker. The reciprocating action of the movable sections causes the fuel which is usually coal to work rearwardly to the end of section c^8 where it falls as ash to a plate c^{21} . The latter is movably supported upon flange rollers c^{22} and is shifted back and forth so as to cause the ashes to work forwardly and drop into the pit a^9 . The movement of the plate c is very slow so as to permit the ashes to give off all of their heat. The rollers c^{22} travel upon tracks c^{23} which are secured to the sides c and c' .

The mechanism for reciprocating the feed plate c^4 and the sections c^5 and c^7 comprises an electric motor c^{24} which is suitably supported in a recess formed at one side of the stoker front; a worm gear c^{25} which is fixed to the armature shaft of the motor and drives a worm wheel c^{26} ; a pinion c^{27} fixed to the shaft for the worm wheel; speed reducing gears c^{28} and c^{29} which are driven one from the other by an intermediate pinion c^{27} ; a crank c^{30} which is formed on the outer end of the shaft for the gear c^{29} ; a link c^{31} which extends between and mechanically connects the crank and the distal end of an arm c^{32} ; and a rock shaft c^{33} to which the arm c^{32} is fixed. The shaft is journaled in bearings c^{34} and imparts reciprocatory movement to the movable plate and sections through a pair of arms c^{35} which are fixed thereon. These arms are pivotally secured to the links c^{17} and are connected to the plate c^4 by a pair of links c^{36} and brackets c^{37} . The gearing is all contained in a housing c^{38} which is secured to the front end of side c' . The ash plate c^{21} is reciprocated by a rock shaft c^{39} which is operated by means of a link c^{40} and an arm c^{41} . The link c^{40} extends between the crank c^{30} and the distal

end of the arm c^{41} while the latter is fixed to the rock shaft c^{39} . This shaft is operatively connected to the plate c^{21} by a pair of arms c^{42} and links c^{43} .

- 5 A transversely extending I-beam c^{44} is supported by the front ends of the sides c , c' and is disposed over the feed plate c^4 . From this beam hang a double row of tiles c^{45} which are positioned adjacent and slightly below the 70 foremost arcuate member a^2 . Arranged in front of these tiles is a gate c^{46} which is movable vertically so as to vary the width of the opening through which the fuel passes from the hopper. The gate is suspended by chains 75 c^{47} which are wrapped around and anchored to a drum c^{48} . This drum is rotated by any suitable means to vary the height of the gate and the latter is protected from the bulk of the fuel by a deflector c^{49} . To increase the 80 capacity of the hopper and adapt it to be loaded from an overhead crane, the front ends of the sides c , c' have plates c^{50} bolted thereto and a sheet c^{51} is provided which operates as a continuation of the inclined member c^3 . 85 25 The lower end of this sheet c^{51} laps the top margin of the inclined member and the upper end is secured to the free ends of a pair of inclined I-beams c^{52} . The latter are connected to a pair of vertically extending I-beams c^{53} by brackets c^{54} . The beams c^{53} are disposed at the sides of the stoker and fit against the side walls a' and a^2 of the furnace. The lower ends of beams c^{53} are embedded in the floor while a cross bar c^{55} joins together 90 30 the upper ends. Inclined braces c^{56} extend between the I-beams c^{52} and the vertical beams and are connected thereto by brackets c^{57} . 95 35 The front of the stoker is formed by three vertically aligned cross members c^{58} , c^{59} , and c^{60} which are spaced apart and form a draft opening c^{61} and an opening c^{62} through which the ashes may be removed from the pit a^0 . These openings are closed 100 40 respectively by a pair of doors c^{63} and c^{64} . A partition plate c^{65} divides the space below the grate sections into a draft chamber c^{66} and an ash chamber c^{67} . This partition is connected at its rear end to the cylindrical 105 45 girder c^{15} and at its front end to the cross member c^{69} . A pair of draft openings c^{70} and c^{71} are formed in the side c of the stoker. These openings are disposed beneath the grate sections c^8 and c^6 respectively and are controlled by dampers c^{74} . A draft is created in the furnace by forcing air under pressure into the draft chamber c^{66} . This is accomplished by means of a fan 10 and a conduit c^{72} which extends between the exhaust opening 110 50 55 60 65 70 75 80 85 90 95 100 105 110 115 120 125 130 135 140 145 150 155 160 165 170 10445 10450 1045

beams 22 and are spaced apart to form an opening 23 whereby the operatives may gain entrance to the enclosing structure. This opening is closed by a sheet metal air-tight door 24 which is supported by hinges at one side thereof. The upper parts 25 of the rear-most side sections are extended and shaped to fit against the I-beams c^{62} and the latter have a sheet metal plate 26 extending thereacross. This plate has an opening 27 formed therein through which the fuel may be dumped into the hopper and its extension. The opening 27 is normally closed by an air tight door 28 which is hinged at its rear end so that it may be lifted into its open position. A sheet metal section 29 closes the space between the standards or I-beams 21 and the upper margin thereof is connected in any suitable manner to the contiguous margin 20 of the plate 26 so as to completely enclose the exposed parts of the stoker and the front of the furnace. The joints between the sections of the supporting elements are hermetically sealed in any suitable manner to render the structure air-tight.

The fan 10 is housed within the enclosing structure and the inlet 30 therefor projects through an opening 31 in one of the sheet metal sections of the side wall 16 so as to be supplied with air from the room. The fan casing 14 is provided with an additional exhaust opening 32 which delivers air under pressure into the structure. Since the openings c^{70} and c^{71} are restricted because of the dampers c^{74} there is a back pressure in the conduit c^{72} which causes the air delivered into the structure to create a pressure in excess of that of the gases in the furnace. As a result of this arrangement there is a tendency for the air to pass inwardly or into the furnace and thus the poisonous and deleterious gases are prevented from escaping into the room and into contact with the stoker operating mechanism. In actual practice it has been found that when the pressure built up within the enclosing structure is equal to about one-half inch of water column, the best results are obtainable. A slide valve 33 is provided to control the exhaust opening 32. This valve together with the dampers c^{74} permits the external and internal pressures to be built up in accordance with actual requirements. While the air pressure in the enclosing structure is reduced when either the fuel door 28 or the door 24 is opened, the fan 10 is preferably of such a capacity as to restore quickly the proper or original pressure.

Since the enclosing structure is made up of sheet metal sections and angle and channel beams it may be fabricated at the factory and shipped in knock-down form to the place of installation where it may be quickly and readily assembled.

The invention is not to be understood as restricted to the details set forth, since these

may be modified within the scope of the appended claims, without departing from the spirit and scope of the invention.

Having thus described the invention, what I claim as new and desire to secure by Letters Patent, is:

1. In combination, a furnace substantially surrounded by air under atmospheric pressure and provided with a fuel opening in the front thereof and a combustion chamber communicating with the opening and adapted to have pressure developed therein, a housing structure built onto and connected directly to the front of the furnace and forming an air-tight chamber around the fuel opening, and means for supplying air to said last mentioned chamber under sufficient pressure to prevent the escape of gases from the combustion chamber through said opening. 75

2. In combination, a furnace provided with an opening and embodying a combustion chamber adapted to have pressure developed therein; a mechanical stoker device for automatically feeding coal to the furnace, said device extending through the opening and having operating parts disposed outside of the furnace, a structure forming a substantially air-tight chamber adjacent the opening and around the exterior parts of the stoker device, and means for supplying air to said last mentioned chamber under sufficient pressure to prevent the escape of gases from the combustion chamber through said opening and around the said exterior stoker parts. 90

3. In combination, an annealing oven having a heating chamber therein and surrounded by air under atmospheric pressure, a furnace provided with a fuel opening and embodying a combustion chamber communicating with the annealing oven, means for supplying air under pressure to the combustion chamber of the furnace in such quantity that pressure is developed in the heating chamber sufficient to exclude the surrounding air when the oven is opened for charging or discharging purposes, means forming a substantially air-tight chamber around the fuel opening, and means for supplying air under pressure to said last mentioned chamber under sufficient pressure to prevent the escape of gases from the combustion chamber of the furnace through the fuel opening. 100

4. In combination, a furnace provided at the front end thereof with means forming an opening through which fuel may be fed, an annealing oven associated with the furnace, means forming a conduit between the heating chamber of the oven and the combustion chamber of the furnace, means for developing a pressure in said chambers greater than that of the surrounding air, a structure enclosing the front end of the furnace only and forming an air-tight chamber adjacent the portion of the furnace having the fuel opening, and means for supplying air to said last men- 120 125 130

tioned chamber under sufficient pressure to prevent the escape of gases from the combustion chamber through said opening.

5. In combination, a furnace provided with an opening and embodying a combustion chamber adapted to have pressure developed therein, a device for mechanically feeding fuel to the furnace extending through said opening and comprising a grate system and a 10 hopper for feeding fuel to said system, the hopper being disposed on the outside of the furnace, a structure forming a substantially air-tight chamber around the hopper, and means for supplying air to said last mentioned chamber under sufficient pressure to prevent the escape of gases from the combustion chamber through the hopper.

6. In combination, a furnace provided with an opening and embodying a combustion 20 chamber adapted to have pressure developed therein, a device for mechanically feeding fuel to the furnace extending through the opening and comprising a grate system and a hopper for feeding fuel to the system, said 25 hopper being disposed on the outside of the furnace, a structure forming an air-tight chamber around the hopper, and means for supplying air to said last mentioned chamber under sufficient pressure to prevent the escape 30 of gases from the combustion chamber through the hopper, said structure having a door therein adjacent said hopper.

7. In combination, a furnace provided with fuel and ash openings in the front thereof and 35 embodying a combustion chamber, a grate system in the furnace arranged to form an ash chamber therebelow, a fan disposed on the outside of the furnace and connected to deliver air under pressure to the ash chamber so as to develop a pressure in the combustion 40 chamber, a structure built onto and connected to the furnace forming a substantially air-tight chamber around the fuel and ash openings, and means for supplying air to said 45 last mentioned chamber under sufficient pressure to prevent the escape of gases from the combustion chamber through said openings.

8. In combination, a furnace provided with fuel and ash openings and embodying a combustion 50 chamber, a grate system in the furnace arranged to form an ash chamber therebelow, a fan disposed on the outside of the furnace and connected to deliver air under pressure to the ash chamber so as to develop a 55 pressure in the combustion chamber, and a structure forming a substantially air-tight chamber around the fuel and ash openings, said fan having a manually controlled outlet for supplying air under pressure to said air-tight chamber.

9. In combination, a furnace provided with an opening in one portion thereof and embodying a combustion chamber in communication with the opening and adapted to have 65 pressure developed therein, a housing struc-

ture other than the building in which the furnace is located, built onto and connected directly to the furnace and forming a substantially air-tight chamber around said opening, and means for supplying air to said last mentioned chamber under sufficient pressure to prevent the escape of gases from the combustion chamber through said opening.

Signed at Chicago, Illinois, this 25th day of February, 1928.

JOSEPH HARRINGTON.
